Des. 237,556
Patented Nov. 4, 1975

237,556

BEVERAGE DISPENSER OR SIMILAR ARTICLE

Roger L. Schlaifer, 1 Valley Forge Place,
Atlanta, Ga. 30318

Filed Jan. 24, 1974, Ser. No. 436,138

Term of patent 14 years

Int. Cl. D15—08

U.S. Cl. D94—3 C

FIG 1

FIG 2

FIG 3

FIG 4

FIG 5

FIG 6

FIG 7

FIG 8

FIG 9

FIG 10

FIG 11

FIG 12

FIG. 1 is a perspective view of a beverage dispenser showing my new design;

FIG. 2 is a top view thereof;

FIG. 3 is a front elevation view thereof;

FIG. 4 is a left side elevation view thereof;

FIG. 5 is a right side elevation view thereof;

FIG. 6 is a rear elevation view thereof;

FIG. 7 is a perspective view of a beverage dispenser showing a modification of my new design wherein the housing is cylindrical in configuration;

FIG. 8 is a top view thereof;

FIG. 9 is a front elevation view thereof;

FIG. 10 is a left side elevation view thereof;

FIG. 11 is a right side elevation view thereof; and FIG. 12 is a rear elevation view thereof.

I claim:

The ornamental design for a beverage dispenser or similar article, substantially as shown and described.
